UNITED STATES PATENT OFFICE.

AXEL EMIL EKLUND, OF BROOKLYN, NEW YORK.

CARBURETER.

1,285,652.

Specification of Letters Patent. Patented Nov. 26, 1918.

Application filed March 2, 1917, Serial No. 151,983. Renewed October 14, 1918. Serial No. 259,103.

To all whom it may concern:

Be it known that I, AXEL EMIL EKLUND, a citizen of the United States, residing at Brooklyn, Kings county, and State of New York, have invented and discovered certain new and useful Improvements in Carbureters, of which the following is a specification.

My said invention relates to carbureters for internal combustion engines, and consists in the combination and arrangements of elements hereinafter described and particularly set forth in the accompanying claims.

The invention has for its purpose to provide a carbureter, whereby the heat from the exhaust gases of the engine may be utilized to vaporize fuel charges from ordinary liquid hydrocarbon, thereby imparting to the vaporizer the highest degree of efficiency.

The invention has for its further purpose to economize space in mounting the carbureter on the engine, and to utilize the heat 25 of the exhaust at its highest temperature; and one in which a constantly heated body initially receives the jets of gasoline and conditions the same for the further heating thereof, which occurs in its passage to the 30 engine cylinder.

Another purpose of the invention is to construct a carbureter of few parts that may be readily assembled or disassembled, and having means for adjustment to vary the 35 amount of gas produced in accordance with the demands of the engine.

The invention is disclosed by way of illustration in the accompanying drawings, wherein—

Figure 1 is a central vertical sectional view of the carbureter, and

Fig. 2 a transverse sectional view thereof taken on the line 2—2 in Fig. 1.

Referring to the construction in further detail, and wherein like reference characters designate corresponding parts, the carbureter consists of a casing or reservoir 3, having a removable cover 4, and adapted to receive the liquid fuel from the source of supply (not shown) through the pipe inlet 5.

A float 6, of any appropriate type, is located within the vessel 3, and automatically operates to raise or lower the valve 7 that controls the flow of gasoline from the supply into said reservoir 3. The valve 7 is mounted on a stem or rod 8, working

through a collar 9 on the cover plate 4, and is adapted to be moved to seat or unseat said valve 7 by the pair of levers 10 that are fulcrumed on the studs 11 secured to the closure plate 4. The outer ends of said levers 10 contact with the upper surface of the float 6, and the inner ends of said levers engage with a collar 12, mounted on the valve stem 8, and by this arrangement, the 65 raising and lowering of the float will seat or unseat the valve 7, as will be understood.

A tubular casing or cylinder 13 is located adjacent the gasoline tank 3 and provides the chamber within which the liquid fuel 70 is vaporized prior to delivery into the engine cylinder; and said cylinder is constructed at one end with an apertured flange 14 for mounting on the motor, and at its other end 15 is closed. The closed end is provided 75 with a plurality of apertures 16 adapted to register, in varying degrees, with similar openings 17 formed in a ring 18 that is adjustably mounted in the cylinder 13, as shown. A hand-gripping piece 19 is secured to the perforated ring 18 and serves for adjusting said ring to regulate the proportion of air to be mixed with the fuel charges.

A butterfly-valve 20 is pivotally mounted 85 in the charge forming chamber at the outlet end thereof for regulating the volume of gaseous mixture to be delivered into the engine. The means for actuating said valve 90 comprises an arm 21 secured to the valve shaft 22, and connected with the rod 23 that also connects with a suitable control.

A jacket 24 is mounted on, and surrounds a portion of the cylinder 13, and is adapted to receive the exhaust gases from the engine 95 through the intake opening 25, and discharges said gases into the muffler, or direct to the atmosphere, through the outlet opening 26. The heat from the exhaust gases within the jacket serves to form and initially 100 heat the fuel charges that are delivered into the cylinder by the suction strokes of the piston. Said nozzle 27 communicates with the fuel reservoir 3 through the passage 28, as shown, and is detachably mounted on a tubular member 29 projecting from the inner wall of the cylinder 13.

It is proposed to have a constantly heated body to receive the jets of fuel issuing from the nozzle 27 and initially disintegrate the 110 same, and to this end a plug 30 projects through the side wall of the cylinder 13, and

has an angular face 31 that receives the fuel jets and deflects the same upwardly in the form of a finely divided spray. The plug 30 is formed with screw threads 32 for readily adjusting the same from the exterior by a suitable tool that engages the notched head 33. By this arrangement it will be observed that the face 31 of the plug may be adjusted toward or from the nozzle 27, all in accordance with the demands or conditions under which the engine is working.

It is obvious that those skilled in the art may vary the details of construction and arrangements of parts without departing from the spirit of my invention, and I therefore do not wish to be limited to such features except as may be required by the claims.

Having thus fully described my said invention, what I claim as new and desire to secure by Letters Patent, is:

1. In a carbureter, the combination of a cylinder providing a fuel mixing chamber, said cylinder having a closed end and provided with means for admitting air into the mixing chamber; means for varying the amount of air admitted, means for admitting a jet of liquid fuel into said chamber, a jacket surrounding the cylinder and adapted to receive the exhaust gases from the engine to heat the mixing chamber, a plug passing through the heating chamber of said jacket and located to receive, initially

vaporize, and deflect the issuing jet of liquid fuel, and controlling means located adjacent the discharging end of the cylinder, substantially as set forth.

2. In a carbureter, the combination of a cylinder providing a fuel mixing chamber, said cylinder having a closed end and provided with means for admitting air into the mixing chamber, means for varying the amount of air admitted, a diagonally disposed nozzle mounted in the cylinder adapted to issue a jet of liquid fuel centrally of the cylinder chamber, a jacket surrounding the cylinder and adapted to receive the exhaust gases from the engine to heat the mixing chamber, a plug passing through the heating chamber of said cylinder jacket and disposed in alignment with the nozzle, and means to receive, initially vaporize, and deflect the jets of liquid fuel issuing from said nozzle, and a controlling valve located adjacent the discharging end of the cylinder, substantially as set forth.

In witness whereof I have hereunto set my hand and seal at Brooklyn, New York, this 25th day of February, A. D. nineteen hundred and seventeen.

AXEL EMIL EKLUND. [L.S.]
